(57) **CLAIM**

The ornamental design for a luggage handle, as shown.

DESCRIPTION

FIG. 1 is a perspective view of a luggage handle in accordance with the present invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a reduced scale, environmental perspective view thereof; and,

FIG. 9 is another environmental perspective view with the handle in a raised position.

The broken lines showing portions of a suitcase are for the purposes of illustrating environment and forms no part of the claimed design.
